Adam Baker Barnhart, New York, N. Y., assignor to Jacqueline Cochran, doing business as J. C.
Laboratories, Roselle, N. J.

Application August 9, 1937, Serial No. 70,944

Term of patent 14 years

To all whom it may concern:

Be it known that I, Adam Baker Barnhart, a citizen of the United States, residing at New York, in the county of New York and State of New York, have invented a new, original, and ornamental Design for a Bottle, of which the following is a specification, reference being had to the accompanying drawing, forming part thereof.

In the drawing Figure 1 is a perspective view of a bottle showing my new design, and Figure 2 is a bottom plan view thereof.

I claim:

The ornamental design for a bottle as shown.

ADAM BAKER BARNHART.
